UNITED STATES PATENT OFFICE.

ALICE BRIGGS, OF UNION CITY, PENNSYLVANIA.

UMBRELLA.

1,250,788.

Specification of Letters Patent. Patented Dec. 18, 1917.

Application filed November 21, 1916. Serial No. 132,639.

To all whom it may concern:

Be it known that I, ALICE BRIGGS, a citizen of the United States, residing at Union City, in the county of Erie and State of Pennsylvania, have invented certain new and useful Improvements in Umbrellas, of which the following is a specification.

My invention relates to new and useful improvements in umbrellas, and more particularly to a folding umbrella.

The primary object of the invention is the construction of an umbrella in such a manner that it may be folded to be carried in a small space.

A further object of the invention is the provision of telescoping ribs and a cover which may be folded when the ribs are telescoped.

A still further object of the invention is the provision of means for folding the cover simultaneously with the telescoping of the ribs.

With these and other objects in view the invention consists in the novel details of construction and arrangement of parts which will be more clearly understood from the following description and drawings in which,

Figure 1 is a vertical section through the umbrella when in raised position,

Fig. 2 is a top plan view of the umbrella in raised position,

Fig. 3 is a side view of the umbrella frame in folded position,

Fig. 4 is a longitudinal section through one of the ribs, and

Fig. 5 is a transverse section on the line 5—5 of Fig. 4, looking in the direction of the arrows.

In the drawings, the numeral 1 indicates the several sections of the stick and said sections are hingedly connected by means of the plates 2 which are connected to the sections by means of the pins or rivets 3. The sections 1 are held in their extended position by means of sleeves 4 which extend over the hinged joint.

The ribs of the umbrella are formed in sections and comprise the tubular members 5 and rods 6 which telescope within the tubular members 5. On their upper ends, the tubular members 5 are provided with the extensions 7 having eyes 8 therein. A longitudinal opening or slot 9 is formed in each of the tubular members 5 and a projection 10 is secured to each rod 6 and ex-

tends through the adjacent slot 9. Each projection 10 is provided with an eye 11, the purpose of which will be presently described.

Rings or ferrules 12 and 13 are slidably mounted upon the upper section 1 of the stick and a spring-catch 14 is provided on the upper section 1 to hold the ring or ferrule 12 in raised position. Brace-bars 15 are pivotally connected to the ring 12 at one end and at the opposite end are pivotally connected respectively to the projections 10 formed on the rods 6. The brace-bars 15 are provided on the upper edges with projections 16 having eyes therein, and braces 17 are each pivotally connected at one end to the ring or ferrule 13 and at the opposite end to the corresponding projection 16. As is shown in Fig. 1 of the drawings, when the umbrella is raised, the brace-bars 15 extend upwardly at an angle from the ring or ferrule 12, and the brace-bars 17 extend downwardly at an angle from the ring or ferrule 13.

A covering 18 of any desired fabric is connected to the ribs, but is only connected to the sections 6 at the lower ends thereof for the purpose presently described. The brace-bars 15 are provided on the upper edges thereof with projections 19 having openings therein, and cords 20 are connected to said projections by passing through the openings, and extend upwardly and through openings in the covering 18, thence 90 extend over the covering and are connected at the point indicated at 21. These cords 20 are used for folding the covering 18 when the ribs are telescoped for folding the umbrella.

Having fully described the details of construction it is thought that the advantages of such an umbrella as well as the mode of operation will be clearly understood. In Fig. 1 of the drawings, I have shown the several parts of the invention with the umbrella in raised position. When it is desired to fold the umbrella, the spring-catch 14 is released and the ring or ferrule 12 slipped downwardly, thereby drawing the tubular sections 5 of the ribs inward or toward the handle-sections 1. The ring or ferrule 13 is raised and, by drawing upon the brace-bars 15, will telescope the sections 6 of the ribs within the tubular sections 5. 110 When the umbrella is to be folded, it is also necessary that the fabric covering 18 be

folded, and to do this, I have provided the cords 20 which are connected to the fabric and to the brace-bars 15. When the brace-bars 15 are lowered by sliding the ring or 5 ferrule 12 the cords will be pulled and will fold the lower portion of the fabric over the top portion.

Having fully described my invention what I claim as new and desire to secure by Letters Patent is:

- 10 1. An umbrella comprising a stick, telescoping ribs connected to said stick, a cover connecting to said ribs, and means for folding the upper and lower parts of the cover in lapped relation to one another where said ribs are telescoped.
- 15 2. An umbrella comprising a stick, telescoping ribs connected to said stick, a cover connected to said ribs, and flexible elements for folding the upper and lower parts of the cover in lapped relation to one another where said ribs are telescoped.
- 20 3. An umbrella comprising a stick, telescoping ribs connected to the stick, braces connecting the ribs and handle, a cover connected to the ribs, and means connected to the braces for folding the cover where said ribs are telescoped.
- 25 4. An umbrella comprising a stick, telescoping ribs connected to the stick, braces connecting the ribs and stick, a cover secured to the ribs, and cords operable by the braces for folding the cover where said ribs are telescoped.
- 30 5. An umbrella comprising a stick, tele-

scoping ribs connected to the stick, braces connecting the ribs and stick, a cover connected to the ribs, and cords connected to the braces, said cords passing through the cover and connected thereto.

40 6. An umbrella comprising a stick, ribs connected to the stick, braces connected to the stick and ribs, said braces having projections on the upper edges thereof, said projections provided with eyes, a cover connected to the ribs, and cords connected to the projections on the braces and to the cover.

45 7. A folding umbrella comprising a sectional stick, ribs connected to the stick, said ribs being formed in sections, one section being tubular and having a longitudinal slot therein and the other section telescoping therein and provided with a projection extending through the slot, a ring slideable 50 on the stick, braces connected to the ring and projection on the telescoping rib section, a second ring slideable on the stick above the first-mentioned ring, braces connected to said ring and first-mentioned braces, a cover 55 connected to the ribs, and cords connected to the first-mentioned braces and cover and operable to fold the latter.

50 In testimony whereof I affix my signature in presence of two witnesses.

MRS. ALICE BRIGGS.
